LIGHTING FIXTURE

Arthur H. White, Cherrydale, Va.

Application May 16, 1936, Serial No. 80,171

2 Claims. (Cl. 240—78)

This invention relates to lighting fixtures and in particular is designed for use in indirect lighting.

The principal object of the invention is to provide a compact lighting unit so constructed that the range and intensity of reflected light may be varied.

Another object of the invention is to provide in a lighting unit a reflector of such design that the light reflected to the ceiling and walls has a square or rectangular outline.

Another object of the invention is to control the light lines of the light reflected.

Still another object of the invention is to provide a closed lighting unit in which the light intensity is not lowered.

Referring to the drawing.

Fig. 1 is a sectional view of the lighting unit showing its several parts in position.

Fig. 2 is a top plan view of the unit with the lens removed.

Figs. 3 and 4 are views in perspective of the preferred form of light adjusting elements.

Fig. 5 is a view partly in perspective and partly in section of a spring member for holding the parts in position.

Referring in detail to the drawing the fixture comprises a lamp body 18 which is substantially of U shape in cross section. The various parts 30 of the lighting unit are held compactly within the lamp body and its upper end is open for the passage of light. The lamp body in use is suspended from a ceiling and the light directed towards the ceiling through its open end.

At the base of the lamp body is provided a suitable arrangement for adjustably mounting a light bulb. In its preferred form the adjusting means 35 comprises a bracket 11 formed of flat sheet material, shown in detail in Fig. 4, having a depressed portion 12 which seats a standard light bulb 1 in a socket 13. The bracket 11 is provided at its outer ends with down turned flanges 15 having apertures therein.

Located on either side of the bracket 11 and 40 adapted to cooperate therewith are similar L shaped brackets 16 shown in detail at Fig. 3. These brackets are formed with flanges 14 and 18 preferably downturned which are adapted to fit the contour of the lamp body near its base and 45 be held in position between the main bracket and the lamp body. One arm of the L shaped bracket is slotted for the greater part of its length and these slots 19 cooperate with the apertured flanges of the main bracket for adjusting the 50 position of the main bracket relative to the lamp

body. Suitable nut and bolt connections 20 may be provided for adjustably holding the several brackets in adjusted position.

Located directly above the brackets 16 and 5 adapted to rest thereon is provided a reflector 21 made up of four similarly shaped reflecting plates 22. These plates are welded or held together in any suitable manner to form a reflector of frusto pyramidal shape. The square inner end of the reflector is adapted to seat on the 10 bracket 16 and the square outer end protrudes slightly above the upper edge of the lamp body so as to eliminate any interference of the lamp body with the reflected rays. The reflector 21 may be fixed in position to the lamp body by suitable 15 bolts 23.

Located within the main reflector 21 I have provided an intensifying reflecting plate 24 which preferably is concave in shape. This reflector is located adjacent the bracket 11 and near the base 20 end of the reflector 21 and is provided with an aperture 25 through which the neck end of a bulb may pass to be received by the socket 13. Radiating from the margin of the aperture are a series of slots 26 which give to the reflector a 25 spring grip by which the reflector is held in position on the light bulb.

The endless spring member 27 shown in detail in Fig. 5 is of substantial V shape in cross section and is adapted to fit between the upper edge of 30 the lamp body and the upper edge of the reflector 21. One side 38 of the spring member fits tightly against the inside of the lamp body while the other edge 29 will lie substantially in a horizontal 35 position forming with the upper edge of the lamp body a shelf, which is adapted to receive a clear glass lens so as to keep the lighting unit dust proof. With such an arrangement no fastening devices are necessary to keep the lens in position.

From the foregoing description it will be seen that I have provided a compact lighting unit which is easily installed and which is adapted to reflect light whose outline is straight lines and wherein the light bulb may be adjusted to vary 45 the extent of the outline of the reflected light.

In installing the above described unit in a room to be lighted, the lamp body is first suspended from the ceiling and the proper light intensity and range determined by varying the distance of the 50 light bulb and intensifying reflector relative to the top of the frusto pyramidal reflector. The outline of light reflected will be of straight line form. Several such units may be positioned from the ceiling so that the total surface of the ceiling 55

may be lighted without having any of the light overlapping.

Having described my invention and the advantages thereof, I do not wish to be limited to the 5 details herein disclosed, otherwise than as set forth in the following claims.

I claim:

1. A fixture for indirect lighting comprising a lamp casing having one end open for the passage 10 of light, a light bulb bracket located within the casing, angle brackets associated therewith and provided with means adapted to permit adjustment of said light bulb bracket, a frusto pyramidal reflector disposed within the casing and having 15 its lower edges resting on said angle brackets and its upper edges lying adjacent the upper edges of the casing, a spring ring disposed between said

reflector and casing edges and a convex lens closing the casing and having its edge resting on said ring.

2. A fixture for indirect lighting comprising a lamp casing having one end open for the passage 5 of light, a light bulb bracket located within the casing, angle brackets associated therewith, and provided with means adapted to permit adjustment of said light bulb bracket, a frusto pyramidal reflector disposed within the casing and having its lower edges resting on said angle brackets, a concave reflector disposed above said brackets and having an opening through which the screw end of a light bulb may pass to be received by said light bulb bracket, said reflectors cooperating to direct 10 the light to the ceiling in a straight lined outline. 15

ARTHUR H. WHITE.
